VENDING MACHINE FOR BOTTLED BEVERAGES

Raoul A. Lambert, Springfield, Mass., assignor to Westinghouse Electric Corporation, East Pittsburgh, Pa., a corporation of Pennsylvania

Application May 23, 1955, Serial No. 36,166

Term of patent 14 years

(Cl. D52—3)

FIG. 1.

FIG. 2.

Fig. 1 is a perspective view of a vending machine for bottled beverages embodying my new design; and

Fig. 2 is a partial side elevational view thereof.

The side of the cabinet not in view is similar to the side in view. The characteristic features of the design reside in the portions shown in full lines.

I claim:

The ornamental design for a vending machine for bottled beverages, substantially as shown and described.
